UNITED STATES PATENT OFFICE.

SAMUEL W. JUNKEN, OF BUFFALO, MINNESOTA.

BLOTTING-PAD.

No. 858,657.

Specification of Letters Patent.

Patented July 2, 1907.

Application filed April 27, 1907. Serial No. 370,062.

To all whom it may concern:

Be it known that I, SAMUEL W. JUNKEN, a citizen of the United States, residing at Buffalo, in the county of Wright and State of Minnesota, have invented a new and useful Blotting-Pad, of which the following is a specification.

This invention relates to an article for the use of persons who do more or less writing; and consists of a blotting pad to be worn on the writing hand in such position that it will always be ready for use without the necessity of dropping the pen when a blotting pad is demanded.

The object of the invention is to provide a cheap, convenient, and easily applied blotting pad for the writing hand, having means for retaining it in such position thereon that it cannot become disarranged and will always be ready for use when needed, thus doing away with the necessity of laying down the pen when a blotting pad is to be used.

Another object of the invention is to provide a shield preferably made of fabric, having an opening for the thumb, and a resilient band on one side which carries a separable attachment for connection to the blotting pad. A wristband is also attached to the shield and provided with a clasp for securing the band around the wrist.

With these and other objects in view the invention consists of a novel construction, combination and arrangement of parts hereinafter described and pointed out in the claims.

In the accompanying drawings:—Figure 1 is a perspective view of the blotting pad applied to a hand. Fig. 2 is a view of the outer side of the blotting pad and shield showing the separable connections between the parts. Fig. 3 is a detail view of a corner of the blotting sheet as seen from the insides.

Similar numerals of reference indicate the same parts on all the figures.

The pad 1 of the invention is made of an absorbent paper commonly known as blotting paper and has an approximately rectangular form with its forward end 2 slightly projecting and having the corners 2^a over the back of the hand rounded. The outline of the pad is not to be confined to that described and shown as it may be cut into any useful or ornamental configuration demanded.

Preferably at each side of the blotting sheet 1 on its inner surface and if desired on the outer surface also, is a strip of tough paper, fabric or other suitable strengthening material 3 attached to the blotting sheet by an adhesive. These pieces of strengthening material may be omitted, but they are intended to reinforce the button holes 3^a in the blotting sheet.

The shield 4 is preferably made of fabric or leather of any suitable kind such as cotton, linen, silk, velvet, glove leather, etc., and in any convenient shape, the only necessary requirements being a place for attaching the wrist band 5 and the blotting sheet 1. An opening 6 for the thumb is desirable but in some designs for the shield it may be omitted. On the outer side of the shield 4 is an elastic band 7 fastened at one end, to the lower inner edge of said shield and extending across the forward end thereof in front of the thumb, it passes beneath two narrow bands or loops 8 on the shield and is connected at its outer end to a buckle 9 on a strap 10 removably attached to the adjacent edge of the blotting sheet by a button 11.

Along the edge of the shield 7 beneath the hand, is a row of buttons, or other fastenings, to which the adjoining edge of the blotting sheet is removably buttoned as shown in Fig. 2. When the shield is provided with a thumb opening 6, the edge of the opening should be protected by some binding material 13.

The wrist band 5 consists of a strip of the same material, preferably, as that which forms the shield and is securely attached thereto by stitching. One end of the wristband is provided with a button 14, the other end by one or more button holes 15 to adjust the wristband to the size of the wrist.

To apply the article, the wristband is separated, the thumb passed through the hole 6 and the shield and pad drawn over the hand in such position that the blotting pad will extend around the outside of the hand, folding over the back for a short distance and for a greater distance under the palm and little finger. The thumb and fingers being free to hold and use a pen, the hand may be moved as desired to dry the ink without losing control of the pen.

While a certain form of separable attachment between the blotting pad and the elastic band 7 has been described, any other suitable variety of separable connecting means may be employed.

Having thus described the invention what is claimed is:—

1. As an article of manufacture, a blotting pad comprising a sheet of absorbent material, a shield, removably attached to said blotting pad, to be applied to the hand and having a wristband fastened thereto, and a resilient band on said shield adapted to be separably attached to said absorbent sheet. 95

2. As an article of manufacture, a blotting pad comprising a sheet of blotting paper, a shield removably attached to one edge of said blotting pad and having a thumb hole, said shield to be applied to the hand, a separable wristband attached to said shield, and a resilient band fastened to said shield and adapted to be separably connected to said blotting sheet. 100

3. As an article of manufacture, a blotting pad comprising a sheet of blotting paper, a shield removably at-

tached thereto, a resilient band fixed to one side of said shield and connected to said blotting sheet by separable connection, and a wristband attached to said shield.

4. As an article of manufacture, a blotting pad comprising a sheet of blotting paper, a shield removably attached thereto, a resilient band secured to and passing across said shield, a strap buckled to said resilient band, and a separable connection between said strap and blotting sheet.

In testimony that I claim the foregoing as my own, I 10 have hereto affixed my signature in the presence of two witnesses.

SAMUEL W. JUNKEN.
